LABORATORIES, INC., OF NEWARK, NEW JERSEY, A CORPORATION OF NEW
YORK.

COIL-WINDING MACHINE.

1,414,679.

Specification of Letters Patent.

Patented May 2, 1922.

Application filed March 22, 1921. Serial No. 454,558.

To all whom it may concern:

Be it known that I, EUGENE T. TURNER, a citizen of the United States, and a resident of Holmes, Dutchess County, and State of New York, have invented certain new and useful Improvements in Coil-Winding Machines, of which the following is a specification.

This invention relates to the construction 10 of flat spiral inductance coils like those covered in my Patent No. 1,372,850 of March 29th, 1921.

These coils each consist of a wire which is wound spirally and interlaced to opposite 15 sides of the radiating arms of a supporting disc of flat insulating material, and the general objects of the invention are to provide a simple and practical machine for automatically winding the wire on these cores.

Other special objects are to provide a machine which will operate rapidly and automatically and which will lay the wire evenly 20 and firmly in the slots of the core.

In the accompanying drawings I have 25 illustrated practical commercial embodiments of the invention, but wish it understood that the physical structure may be modified in various ways without departing from the true spirit and scope of the invention.

Figure 1 is a side view of the machine.
Figure 2 is a top plan view of the same.

Figure 3 is an enlarged cross sectional view as taken on substantially the plane of the line 3—3 of Figure 2.

Figures 4 and 5 are broken part sectional detail views illustrating the winding of the wire to opposite sides of the radiating arms of the core disc.

Figures 6 and 7 are broken side and plan views respectively of a modified form of drive.

In the machine illustrated, the flat core disc 10 is temporarily supported, during the winding operation, on a shaft 11, being detachably secured thereon between relatively fixed and movable clamping discs 12 and 13, the latter having a screw-threaded connection at 14 with the end of the supporting shaft, and being provided with a wing nut or other hand-hold 15 by which it can be readily turned to secure the core in position.

The wire, which is designated 16, is wound in the slots 17 provided between the radiat-

ing arms of the core and to insure a definite position of the core on the supporting shaft, 55 I have shown the fixed clamping flange 12 as provided with an outstanding finger 18 having an angularly turned end as shown at 19 in Figure 3 to enter in the foot of one of these slots when the core is slipped over the 60 end of the shaft.

To weave the wire back and forth to opposite sides of the radiating arms, as the core is rotated, I provide a tubular wire guide 20 through which the wire passes and which in the machine shown, is reciprocated to opposite sides of the central plane of the core disc by means of an oscillating arm 21 which is pivoted at 22 on the base of the machine and is swung back and forth by a 65 link connection 22' pivoted to the swinging arm at 23 (Figure 3), and connected with a strap 24 encircling the eccentric 25 on the drive shaft 26, which in this particular machine, stands at a right angle to the core 70 shaft 11.

As the winding builds up in the slots, it becomes necessary to relatively lower the point at which the wire is guided so as to lay the wire firmly in the slots on top of the 80 preceding convolutions and so as to avoid the corners of the radiating arms. This will be understood particularly from Figures 1 and 4.

To thus keep the lay of the wire at the 85 proper level or angle, I provide, in the present machine, means for automatically lowering the wire guide as the winding progresses, said means comprising a snail cam 27 engaged by an arm 28 on the rock shaft 29 90 which carries an outstanding bow or yoke 30 having a straight guide or track 31 at the free end thereof on which the wire guide 20 rests, said wire guide being vertically 95 slidable in a slot 32 in the upper end of the swinging arm so that it may follow the lowering movement of the supporting yoke.

The main drive shaft is operated in the present disclosure by a belt engaged over a pulley 33 fixed on said shaft and this pulley 100 is also shown provided with a handle 34 by which the shaft may be turned, if desired, when setting up the parts ready for operation. This also enables the machine being operated by hand in case no power is available.

In the first form of the invention shown, the core supporting shaft 11 is operated intermittently by the engagement of the ends of a transverse pin 35 on said shaft with successive openings 36 provided therefor in a drive disc 37 fast on the shaft 11. To hold the shaft 11 each time it is advanced, this disc is shown as provided with ratchet shoulders 38 engaged by a holding pawl 39.

10 The snail cam is shown as carried by a shaft 40 and as intermittently driven by the engagement of an outstanding tooth 41 on shaft 11 with the teeth of a gear 42 fast on said cam shaft. This cam shaft likewise is 15 shown as held against retrograde movement by a holding pawl 43 engaging with the teeth of this gear.

To steady the radial arms of the core while the wire is being wound thereon, I 20 have shown an overstanding guide 44 carried by a rock shaft 45 and provided with a slot 46 receiving the outer ends of the arms. This particular method of mounting this guide enables the same being swung upward 25 out of the way when the core is being positioned on its supporting shaft, said arm being held in its downward position by a weight 46' adjustably secured by a screw 47, the downward motion of the guide being 30 limited by an arm 48 contacting with a suitable stop shoulder 49 (Figure 1).

The operator is automatically notified in the present disclosure when the coil is fully wound, by a signal consisting of the bell or 35 gong 50 arranged to be struck by the hammer 51 carried by a lever 52 pivoted on the base at 53 and held by the spring 54 in engagement with a cam element 55 on shaft 40.

At the coil starting position, the snail cam 40 may be provided with a notch 56 into which the point of the supporting arm 28 will drop when the parts are in the proper position to commence the winding of a core.

In an alternative method of operation, the 45 core shaft is driven continuously instead of intermittently as heretofore described. Thus as shown in Figures 6 and 7, the core shaft may carry a spur gear 60 engaged by a pinion 61 on shaft 62 which latter is driven 50 by bevel gearing 63 from the main drive shaft 26. With this construction the parts are so timed that the core shaft is being continuously rotated at relatively slow speed 55 while the wire guide is oscillated to properly lay the wire in the slots.

To keep the wire under proper tension, I have shown the same in Figures 1 and 2 as being first led over a guide sheave 65 slidably mounted on a support 66 and thence 60 down under a second guide sheave 67 carried by a spring support 68, the wire passing from this last guide directly to the traversing guide.

It will be apparent from the foregoing 65 that upon rotation of the main driving shaft,

the core will be rotated, either intermittently, as in the first instance, or continuously, in the case of the modified form of the invention, and that in this movement of the core, the wire will be interlaced to opposite sides of 70 the radiating arms of the core, as shown in Figure 4.

It will be evident also that as the convolutions build up in the slots, the variation in angularity between the wire and core will 75 be compensated for by the automatic lowering movement of the traversing wire guide, said guide by such lowering motion serving to keep the wire clear of the corners of the radiating arms and to seat the wire firmly 80 in the slots provided therefor. In addition to the straightening and tensioning effect exerted on the wire by the guide sheaves 65, 67, a braking force may be applied to the wire to cause it to lie snugly alongside the 85 arms and in the slots provided in the core disc. The slotted guide for the free ends of the arms is of particular value when this additional tension is applied to the wire 90 since it steadies these arms and keeps them from being bent to one side or the other of the central plane of the disc.

What I claim is:

1. In a machine of the character disclosed, means for rotating a slotted core, a wire 95 guide, means for traversing said wire guide to the opposite sides of the central plane of the slotted core to thereby lay the wire in the slots in the rotation of the core and means for gradually lowering said guide 100 with respect to the axis of the core as the wire builds up in the slots.

2. In a machine of the character disclosed, a supporting shaft provided with a clamping flange and having a screw threaded portion projecting beyond said flange, a slotted core disc engageable over said screw threaded portion of the shaft, a clamp nut on said screw threaded portion for engagement with the core disc and a member carried by the flange provided with an angularly turned finger to engage in one of the slots in the core disc.

3. In a machine of the character disclosed, means for rotating a slotted core, a cam operated in synchronism with said means, a support shifted by said cam and a wire-laying guide positioned by said support, the cam and support having cooperating parts to indicate the starting position of the cam.

4. In a machine of the character disclosed, means for rotating a slotted core, a cam operated in synchronism with said means, a support shifted by said cam, a wire-laying guide, positioned by said support and a signal device operated by said cam.

5. In a machine of the character disclosed, a rotating core support, a slotted oscillating arm, a wire guide engaged in the slot in said arm, an arm for positioning the wire guide

in said slot and means for shifting said positioning arm as the core support is rotated.

6. In a machine of the character disclosed, 5 a rotary core support, a support shiftable to opposite sides of the central plane of a core on the core support, a wire guide adjustably mounted on said shiftable support and a positioning member for said wire 10 guide automatically shifted in the operation of the rotary core support and including a track member directly engaging and positioning the wire guide.

7. In a machine of the character disclosed, 15 a rotary core support, a support shiftable to opposite sides of the central plane of a core on the core support, a wire guide adjustably mounted on said shiftable support and a positioning member for said wire 20 guide automatically shifted in the operation of the rotary core support and including a yoke pivotally supported at one end and having a track portion at the opposite end engaging the wire guide.

25 8. In a machine of the character disclosed, a shaft provided with means for securing a slotted core disc thereon, a yoke having arms standing at opposite sides of a core secured on said shaft and provided with a 30 track portion connecting the arms at one end, the opposite ends of the arms being pivotally supported, a wire guide engaged by said track portion, means for reciprocating said wire guide and for rotating the supporting shaft.

9. In a machine of the character disclosed, 40 a shaft provided with means for securing a slotted core disc thereon, a yoke having arms standing at opposite sides of a core secured on said shaft and provided with a track portion connecting the arms at one end, the opposite ends of the arms being pivotally supported, a wire guide engaged by said track portion, means for reciprocating 45 said wire guide and for rotating the supporting shaft and means for automatically swinging the yoke about its pivotal center.

10. In a machine of the character disclosed, 50 a core supporting shaft, a drive shaft arranged substantially at right angles to said core supporting shaft, drive gearing from said drive shaft to the core supporting shaft, an eccentric on the drive shaft, a wire guide supported to travel to opposite 55 sides of the central plane of the core on the core supporting shaft and operating connections from said eccentric to said wire guide.

11. In a machine of the character disclosed, 60 a core supporting shaft, a drive shaft arranged substantially at right angles to said core supporting shaft, drive gearing from said drive shaft to the core supporting shaft, an eccentric on the drive shaft, a 65 wire guide supported to travel to opposite

sides of the central plane of the core on the core supporting shaft, operating connections from said eccentric to said wire guide and including a swinging arm to which the eccentric is connected, said arm having a slot 70 receiving the wire guide and means for automatically shifting said wire guide in said slot.

12. In a machine of the character disclosed, 75 a core supporting shaft, a drive shaft arranged substantially at right angles to said core supporting shaft, drive gearing from said drive shaft to the core supporting shaft, an eccentric on the drive shaft, a wire guide supported to travel to opposite sides of the 80 central plane of the core on the core supporting shaft, operating connections from said eccentric to said wire guide, cam mechanism driven from the core shaft and positioning means for the wire guide operated 85 by said cam mechanism.

13. In a machine of the character disclosed, 90 a shaft provided with means for securing a slotted core thereon, a disc on said shaft, a driving member engaging said disc and a main drive shaft for operating said driving member, said driving member consisting of a transverse pin on said drive shaft and the disc having spaced openings 95 therein to be engaged by the protruding ends of said pin.

14. In a machine of the character disclosed, 100 a shaft provided with means for securing a slotted core thereon, a disc on said shaft, a driving member engaging said disc, a main drive shaft for operating said driving member, said driving member consisting of a transverse pin on said drive shaft and the disc having spaced openings 105 therein to be engaged by the protruding ends of said pin and pawl and ratchet mechanism for holding the disc against retrograde movement.

15. In a coil winding machine of the character disclosed, 110 a rotating support for a slotted core, a vibrating arm, a wire guide longitudinally slid able on said arm and carried thereby to opposite sides of a definite plane of a core on the core support, a positioning member for the wire guide having a 115 sliding connection with said guide so as not to interfere with the vibrating movements thereof and means for shifting said positioning member as the winding progresses to thereby vary the position of the wire 120 guide on the vibrating arm.

16. In a coil winding machine of the character disclosed, 125 a shaft provided with means for securing a slotted core thereon, a wire guide positioned to direct the wire in a substantially horizontal plane to the slots in the slotted core, means for traversing said guide to opposite sides of the core and means for substantially continuously varying in one direction the relation of the core support 130

and wire guide vertically one with respect to the other during the traversing motions of the guide to thereby change the angle of direction in accordance with the building up 5 of the wire in the slots.

17. In a coil winding machine of the character disclosed, a support for a core having radiating arms with slots therebetween, a wire guide, means for producing relative rotary movement of said core support and wire guide and for relatively shifting the wire guide and slotted core to opposite sides of a common plane, to thereby spirally interweave a wire directed by the guide into the 15 slots between the radiating arms of the core and means for automatically gradually lowering the wire guide with respect to the tips of the radiating arms to thereby cause the wire to avoid the ends of the arms as the 20 winding builds up in the slots.

18. The structure of claim 17 in which the automatic means comprises a slow motion

cam and an arm positioned thereby and having a loose connection with the wire guide.

19. In a coil winding machine of the character disclosed, a support for a core having radiating arms with slots therebetween, a wire guide, means for producing relative rotary movement of said core support and wire guide and for relatively shifting the wire guide and slotted core to opposite sides of a common plane to thereby spirally interweave a wire directed by the guide into the slots between the radiating arms of the core and means for automatically shifting the wire guide and core support with respect to each other to gradually lower the wire with respect to the tips of the radiating arms to cause the wire to avoid the ends of the arms as the winding builds up the slots. 40

In witness whereof, I have hereunto set my hand, this 9th day of March, 1921.

EUGENE T. TURNER
